(57) **CLAIM**

The ornamental design for a universal controller holster, as shown and described.

DESCRIPTION

FIG. 1 is a left side perspective view of a universal controller holster showing our new design in assembled condition; FIG. 2 is a right side perspective view of the universal controller holster in assembled condition; FIG. 3 is a front view of the universal controller holster in assembled condition;

FIG. 4 is a rear view of the universal controller holster in assembled condition;

FIG. 5 is a left side view of the universal controller holster in assembled condition;

FIG. 6 is a right side view of the universal controller holster in assembled condition;

FIG. 7 is a top view of the universal controller holster in assembled condition;

FIG. 8 is a bottom view of the universal controller holster in assembled condition;

FIG. 9 is a perspective view of the universal controller holster in assembled condition as used by a user to hold a controller;

FIG. 10 is an exploded left side perspective view of the universal controller holster;

FIG. 11 is an exploded right side perspective view of the universal controller holster;

FIG. 12 is an exploded front view of the universal controller holster;

FIG. 13 is an exploded rear view of the universal controller holster;

FIG. 14 is an exploded left side view of the universal controller holster;

FIG. 15 is an exploded right side view of the universal controller holster;

FIG. 16 is an exploded top view of the universal controller holster; and,

FIG. 17 is an exploded bottom view of the universal controller holster.

(Continued)

Any broken lines illustrative of environmental structure in the drawings are not part of the design sought to be patented.
